(57) CLAIM

The ornamental design for an electric fan, as shown and described.

DESCRIPTION

FIG. 1 is a front, right side and top perspective view of an electric fan showing my new design (with its upper body tilted slightly upwardly in this figure only);

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.
